Primary Examiner — Ricky Pham*(74) Attorney, Agent, or Firm* — Edward S. Sherman**CLAIM**

The ornamental design for a cookware vessel, as shown and described.

DESCRIPTION

FIG. 1 is a perspective view of the “cookware vessel”, showing my new design;

FIG. 2 is an exterior side elevation view thereof; all side elevations views being identical as the “cookware vessel” is circular;

FIG. 3 is a cross-sectional view taken through line 3-3 of FIG. 4;

FIG. 4 is a top plan view thereof; and,

FIG. 5 is a bottom plan view thereof.

The broken lines in FIGS. 1-5 are for illustrative purposes only, depicting the environment of the new design, forming no part thereof as claimed.
